DESIGN FOR A VASE

Maurice Exelmans, Paris, France, assignor to Verlys of America, Inc., New York, N. Y., a corporation of New York

Application March 31, 1937, Serial No. 68,494

Term of patent 7 years

To all whom it may concern:

Be it known that I, Maurice Exelmans, a citizen of the Republic of France and a resident of Paris, France, have invented a new, original, and ornamental Design for a Vase, of which the following is a specification, reference being had to the accompanying drawing, forming a part hereof.

The figure is a perspective view of a vase, showing my new design. Both sides of the vase have the ornamental design as shown.

I claim:

The ornamental design for a vase, as shown and described.

MAURICE EXELMANS.
